CLAIM

The ornamental design for a battery terminal cleaner, as shown and described.

DESCRIPTION

FIG. 1 is a top, front and side perspective view of a battery terminal cleaner showing my new design, the undisclosed side being the same in appearance as the side shown;

FIG. 2 is a reduced side elevational view thereof;
FIG. 3 is a rear elevational view thereof; and,
FIG. 4 is an enlarged top plan view thereof, the bottom being a mirror image.

FIG.1.

FIG. 3.

FIG. 2.

FIG. 4.
